US00D707921S

(12) **United States Design Patent**
Tanaka et al.

(10) **Patent No.:** US D707,921 S
(45) **Date of Patent:** ** Jul. 1, 2014

(54) **SPORT TIGHTS**

(71) Applicant: **Wacoal Corp.**, Kyoto (JP)

(72) Inventors: **Fumiko Tanaka**, Kyoto (JP); **Nozomu Seike**, Kyoto (JP); **Jo Miyake**, Kyoto (JP)

(73) Assignee: **Wacoal Corp.**, Kyoto (JP)

(**) Term: **14 Years**

(21) Appl. No.: **29/464,705**

(22) Filed: **Aug. 20, 2013**
